UNITED STATES PATENT OFFICE.

MAX SALDIN, OF NEW YORK, N. Y., ASSIGNOR TO JOHN H. BOYCE AND HARRY R. BOYCE,
COPARTNERS COMPOSING THE FIRM OF JOHN H. BOYCE & SON, OF NEW YORK N. Y.

UNDERSHIRT AND SIMILAR GARMENT.

No. 910,418.

Specification of Letters Patent.

Patented Jan. 19, 1909.

Application filed July 3, 1908. Serial No. 441,828.

To all whom it may concern:

Be it known that I, MAX SALDIN, a citizen of the United States, residing at Brooklyn, city of New York, county of Kings, and State 5 of New York, have invented certain new and useful Improvements in Undershirts and Similar Garments, fully described and represented in the following specification and the accompanying drawings, forming a part of 10 the same.

This invention relates particularly to ladies' undershirts or vests, but is applicable also to other similar underwear, such as union suits and the like, the object of the invention being to provide an improved garment of this class in which the shoulder pieces or straps used for supporting the garment on the shoulders shall be less liable to slip off the shoulders than in such garments 20 now in use, and which shall be simple and cheap of manufacture, and attractive in appearance.

The improved undershirt or vest is made of a fabric cylinder, open at the top for the 25 arms, and with a deep central narrow V front and back, from the edges of which the shoulder pieces or straps extend so that these straps are brought well inward toward the center of the body and thus are held from 30 slipping off the shoulders.

The garment may be made by simply cutting off the fabric cylinder squarely, or approximately squarely, across the fabric, slitting the fabric centrally to form the V, either 35 with or without cutting out the material on opposite sides of the V, according to the character of the garment and width of opening desired, and then finishing the top of the garment and V and forming the shoulder 40 straps in any suitable manner.

In the accompanying drawing forming a part of this specification, the invention is illustrated as applied in its preferred form, a ladies' undershirt or vest embodying the invention being shown in front view, slightly perspective.

Referring to the drawing, A is the body of the garment, formed of a fabric cylinder of knit fabric and preferably knit in the form of 50 a cylinder. At the top, the body is open to form arm-holes 10, and has a deep central

notch, forming a substantially V opening 11 in front and back between the wide side portions 12 of the body below the arm-holes 10. The top of the body and the edges of the V 55 are finished with lace-work 13, which forms a binding for the garment edges and also extends over the shoulders and with the tapes a, b, c looped through it forms the shoulder pieces or straps B extending from front to 60 back of the garment at the outer edges of the V opening and the inner edges of the body portions 12.

The tapes a, b, as shown, extend around the arm openings 10 and tie at the front of 65 the shoulder straps, and the tape c extends about the V opening and inner edges of the straps B and ties at the bottom of the V in front to form a draw-string for the V. It will be understood, however, that this arrangement of tapes, and the construction of the shoulder straps may be varied.

It will be understood that the V-opening is spread and drawn up so as to be wider and less deep when the garment is worn, but the 75 broad body portions 12 below the arm openings 10 and the location of the shoulder straps assure such a position and pull on the latter that they are not liable to slip off the shoulders. The V-opening is shown as cut 80 to the same depth in the front and back, but it will be understood that this is not essential.

What I claim is:

1. An undershirt or similar under-garment 85 formed of a knit fabric cylinder open across the top to form arm openings and having at the top a narrow central notch extending a considerable distance into the garment at the front and back of the garment, and shoulder 90 pieces or straps at the junction of the arm openings and notch and near the middle of the shirt body.

2. An undershirt or similar under-garment 95 formed of a one piece knit fabric cylinder open across the top to form arm openings and having at the top a narrow central notch, bindings extending around each arm opening and over the shoulder, binding extending around the central notch and over the 100 shoulder, said bindings being combined to form shoulder pieces or straps extending over

the shoulder from the junction of the arm openings and central notch and near the middle of the shirt body, and separate draw tapes extending through the arm opening 5 bindings and shoulder straps, and a draw tape extending through the central notch binding and shoulder straps.

In testimony whereof, I have hereunto set my hand, in the presence of two subscribing witnesses.

MAX SALDIN.
